UNITED STATES PATENT OFFICE.

HERBERT E. VAN DORN AND JOHN McWILLIAMS STONE, OF CHICAGO, ILLINOIS.

ELECTRIC COUPLER.

Application filed May 23, 1921. Serial No. 471,920.

To all whom it may concern:

Be it known that we, HERBERT E. VAN DORN and JOHN McWILLIAMS STONE, citizens of the United States, residing at Chicago, county of Cook, State of Illinois, have invented a certain new and useful Improvement in Electric Couplers, and declare the following to be a full, clear, and exact description of the same, such as will enable others skilled in the art to which it pertains to make and use the same, reference being had to the accompanying drawings, which form a part of this specification.

Our invention has for its object to produce a simple and novel electric and air coupler which may be attached to a car coupler and enter into and out of coupled relation with a cooperating member simultaneously with the coupling and uncoupling of the car couplers.

The various features of novelty whereby our invention is characterized will herein-after be pointed out with particularity in the claims; but, for a full understanding of our invention and of its object and advantages, reference may be had to the following detailed description taken in connection with the accompanying drawings, wherein:

Figure 1 is a top plan view of our improved coupler;

Fig. 2 is a side view, showing the door open in full lines and closed in dotted lines;

Fig. 3 is a detail of one of the door hinges;

Fig. 4 is a front elevation of the coupler; and

Fig. 5 is a section on an enlarged scale taken approximately on line 5—5 of Fig. 4.

Referring to the drawings, 1 represents a wide, flat, shallow casing open at the front end and open at the bottom except adjacent to the front end where it is provided with a cross-piece, 2. The opening in the bottom may be detachably closed by means of a plate, 3. Two air pipes, 4 and 5, overlie the top of the casing and are attached at their front ends to the casing at the longitudinal center thereof; the casing being provided with a thick vertical partition or wall, 6, at the middle, this wall having therein air passages, 7 and 8, surrounded at their front ends by suitable gaskets or yieldable washers, 9, and connected at their rear ends to the pipes 4 and 5 respectively. When two couplers are brought together in coupled relation to each other the air lines on two cars are connected through the passages 7 and 8. The rear ends of the pipes 4 and 5

pass through suitable perforated ears, 10, rising from the top of the casing. Within the front end of the casing is a body of insulating material in which are slidably mounted yieldingly-held contact members, there being a group of contact members in each of the two compartments into which the casing is divided by the central partition, 6. The two bodies of insulating material may be constructed in any suitable way. In the arrangement shown, each is made up of a series of individual blocks, 11, lying side by side and fastened together by means of a bolt, 12, passing through the same; a second bolt, 13, being adapted to pass through the insulating material and also through the casing to secure the insulating material in the casing. The insulating blocks are molded or otherwise fashioned so that each block forms with the adjacent block a series of seats for contact members. In the arrangement shown, each seat comprises a rectangular passage or bore, 14, extending inwardly from the front of the insulating material and partway through the block, together with a cylindrical bore or passage, 15, extending from the rear end of the bore or passage, 14, out through the rear end of the block. Each contact piece comprises a cylindrical stem, 16, having at the front end thereof a rectangular head, 17. Behind each head, within the part 14 of the seat, is a spring, 18, which yieldingly holds the contact in its forward position. On the rear end of each of the stems of the contact pieces is a nut, 19, and a lock nut, 20, the latter being made elongated in the axial direction and having an opening, 21, into which the end of a wire may be inserted; a set screw, 22, serving to clamp the wire in place.

The number of contacts in each group, that is, in each half of the casing, is the same and the disposition of the contacts in the two groups is similar; the contacts being symmetrically disposed relatively to the central air ports.

A cable of wires or conductors may be led into the casing through a nipple, 23, extending rearwardly from the rear wall of the casing. Around the front end of the casing and projecting beyond the insulating material is a rim, 24, of rubber. The parts are so proportioned that the contacts normally tend to project beyond the plane of the front edge of the rim so that when

two couplers come into coupled relation to each other the contacting contact pieces press each other back and, just before the coupling is completed, the two rubber rims 5 come into engagement with each other and form a tightly sealed joint between the two couplers, thus preventing the entrance of moisture or dirt.

When the coupler is idle it is desirable 10 that the contacts be covered so as not to leave the same exposed. We have therefore provided a door which may readily be opened and closed and be securely held in either its open or closed position when brought into 15 that position. The door may conveniently consist of a rectangular frame, 25, slightly larger than the rubber rim, a sheet metal plate, 26, being secured to and extending across the frame. The door is provided at 20 one long edge with hinge ears, 27, and on the front of the casing are downwardly-projecting co-operating hinge ears, 28. Pintles, 29, pass through cooperating hinge ears. On each side of the casing is a spring, 25 30, the rear end of which is attached to a point at the rear end of the casing while the front end is attached to the end of the door at some distance from the hinge axis. The parts are so proportioned that when the 35 door is swung upwardly into its closed position the springs act in a direction to hold it closed, as illustrated in dotted lines in Fig. 2; while, when the door is swung open so as to lie underneath the casing, the 40 springs act to hold it open. The openings, 31, in the hinge ears 27 are preferably larger in diameter than the pintles so as to permit the door to shift bodily to some extent. This is desirable so that in case two couplers 45 come together while their doors are closed, the movements of the doors will not be confined to true angular movements around their hinge axes, but may be bodily movements longitudinally of the coupler; thus distributing the pressure uniformly in the contact pieces behind the same; it being understood that the door, when closed, rests

against the front ends of the contact pieces as shown in Fig. 5. In order to avoid damage to the door or to the contact pieces when 50 the door strikes against the latter, we prefer to place on the inner side of the door a cushioning layer, 32, the cushioning layer being also preferably made of a material which has insulating properties. If desired, a 55 cushioning layer, 33, may be placed on the exterior of the door.

The casing is provided with suitable ears, 34, 35, 36 and 37, projecting upwardly and outwardly from the same for the purpose 60 of securing the electrical coupler to the under side of a car coupler.

While we have illustrated and described with particularity only a single preferred form of our invention, we do not desire to 65 be limited to the exact structural details thus illustrated and described; but intend to cover all forms and arrangements which come within the terms employed in the definitions of our invention constituting the 70 appended claim.

We claim:

In an electric coupler, a casing open at the front end, a plurality of longitudinally-movable contacts yieldingly supported in 75 said casing so as normally to project beyond the front end of the same and have capacity for longitudinal movements in the inward direction, a door hinged at one edge underneath the casing and adapted to swing 80 from a position in front of and adjacent to the contacts to a position underneath the casing, and a spring acting on the door to hold it in either its open or its closed position, the hinge connection between the door 85 and the casing including a pin arranged in an opening considerably larger than the pin to permit the door to move bodily toward and from the front end of the casing when the door is in its closed position. 90

In testimony whereof, we sign this specification.

HERBERT E. VAN DORN.
JOHN McWILLIAMS STONE.
